AIR OUTLET DEVICE AND METHOD OF
PRODUCING SAMEFriedrich Honerkamp, New York, N. Y., assignor
to Anemostat Corporation of America, a corpo-
ration of Delaware

Application December 11, 1941, Serial No. 422,585

15 Claims. (Cl. 98—40)

This invention relates to the art of ventilation, and has particular reference to improvements in outlet devices for effecting diffused or substantially draftless delivery of fresh or treated air from air supply ducts into rooms or other enclosures for ventilating or air conditioning purposes.

Generally speaking, the object of the invention is to provide a simple, practical, highly efficient, low-cost device for the purpose stated and to provide a simple, practical method for the rapid, low-cost production of the same.

With the foregoing and other objects in view, which will become more fully apparent as the nature of the invention is better understood, the same consists in an air outlet embodying the novel features of construction, combination and arrangement of parts, and in the novel method steps of producing the same, as will be herein-after more fully described, illustrated in the accompanying drawings and defined in the appended claims.

In the accompanying drawings, wherein like characters of reference denote corresponding parts in related views:

Figure 1 is a top plan view of an air outlet device according to one practical embodiment of the invention.

Figure 2 is a central, vertical section through the device.

Figure 3 is a detail view illustrating a slight modification of the device.

Figure 4 is a plan view of a pre-formed blank from which the device may be produced in accordance with the method of the invention.

Figure 5 is a fragmentary perspective view of the device.

Figure 6 is a top plan view of a pre-formed blank from which an alternative form of the device may be produced in accordance with the method of the invention.

Figure 7 is a central, vertical section through the pre-formed blank shown in Fig. 6.

Figure 8 is a view similar to Fig. 7 showing the form of the device after the pre-formed blank has been manipulated in accordance with the method of the invention.

Figure 9 is a top plan view of the completed alternative form of the invention as shown in Fig. 8; and

Figure 10 is a detail sectional view illustrating a modification of the Figs. 8 and 9 form of the invention.

Referring to the drawings in detail, first to Figs. 1, 2 and 5 wherein is illustrated an air out-

let device constructed in accordance with one practical embodiment of the invention, it will be observed that said device comprises, generally speaking, a series of successively larger, horizontally disposed, concentric, air intercepting rings of flat sheet material, designated as 10, spaced successively outwardly and upwardly with respect to one another and connected together at their adjacent edges by annular rows of vertically disposed web elements 11, whereby an annular row of air outlet openings 12 is provided between each adjacent two of said air intercepting rings. It will further be observed that the outermost ring 10 has extending upwardly therefrom, outwardly of the outermost row of air outlet openings 12, a neck 13 for use in attaching the device to an air supply duct in air receiving relationship thereto. Accordingly, when the device is attached to an air supply duct, some of the air flowing from the duct to the device may flow directly downwardly through the air outlet openings 12, the amount of air so flowing being dependent, of course, upon the areas of the openings 12 and preferably being only a minor portion 15 of the total volume of the supplied air. On the other hand, the remainder of the supplied air, and preferably by far the major portion of the total volume thereof, will be intercepted and deflected laterally outward from the device in superimposed layers by the rings 10. Thus, the supplied air will be delivered from the device in diffused or substantially draftless form, particularly since the layers of air deflected laterally outward by the rings 10 will intercept, intermix 20 and produce diffusion of the air flowing downwardly through the openings 12 at the outer sides of said rings.

The rings 10, the web elements 11 and the neck 13 may all be separate from one another and may be connected together in any suitable manner, or some or all of them may be integral with one another. Moreover, the width of the rings 10 and the length and width of the openings 12 may be varied, as may the width of the webs 11, while said webs may be of any desired length or height to space the rings 10 any desired distances apart vertically. Furthermore, the web elements 11 may be disposed in any desired planes relative to the device, but preferably they are disposed substantially radially and, if desired, at inclinations to the vertical, as shown in Fig. 3, so as to act upon the downwardly flowing air impinging thereagainst to deflect it laterally and thus impart a whirling, diffusing mo-

tion to the air flowing laterally outward from the air intercepting rings 10.

While the device as generally described may be produced in any desired manner, its construction, exclusively of the neck 13, lends itself to practical, rapid, low-cost production from a single sheet or disk of any suitable sheet material by a method involving only a minor number of simple manufacturing steps. In this connection and referring particularly to Fig. 4 of the drawings, A designates an originally plain, flat disk of any suitable sheet material and a designates, generally, successively larger, annular, concentric bands of slits formed in said disk in any desired manner and serving to divide said disk into the aforementioned air deflecting rings 10, of which there may be any desired number depending upon the number of bands of slits that are provided in the disk.

Each band *a* of slits comprises an inner, annular row of slits *b* and a concentric, annular, outer row of slits *c*, and in accordance with the invention the slits of each row of each band *a* are disposed in end to end spaced apart relationship. Moreover, the slits *b* and *c* of both rows of each band *a* are equal, or approximately equal, in length and the slits of the respective rows of each band are disposed in pairs aligned with each other radially with respect to the center *d* of the disk A around which the bands of slits *a* are concentrically disposed, thereby defining the aforementioned web elements 11. Furthermore, each band *a* of slits includes diagonal slits *e* connecting corresponding adjacent ends of the inner and outer slits *b* and *c* of adjacent pairs in the band so that there is provided between each two adjacent of the web elements 11 a pair of substantially V-shaped elements *f* and *g*, one joined to one end of one of the web elements and to the ring 10 inwardly of the band *a* of slits, and the other joined to the adjacent end of the other of the web elements of the pair and to the ring 10 outwardly of the band *a* of slits.

After providing the disk A with the bands *a* of slits as described, adjacent rings 10 of the disk are, in any suitable manner and by any desired means, rotated in their planes and in opposite directions relative to each other and, at the same time, are shifted axially relative to each, which results in the web elements 11 being swung toward positions at right angles to the planes of the rings 10 and thereby providing the aforementioned annular rows of openings 12 between adjacent of the rings 10 while maintaining said rings connected together in parallel planes but in axially offset relationship to each other.

When adjacent rings 10 are rotated and shifted axially relative to each other the webs 11 naturally will tend to bend along lines extending between corresponding ends of the respective pairs of inner and outer slits *b* and *c* of the bands *a* as indicated by the dotted lines *h* in Fig. 4 and therefore any special control of the lines of bend of said webs may not be necessary. Preferably, however, the method of producing the device includes controlling bending of the webs 11 along the lines *h* in any suitable manner and by any desired means to insure uniformity in the bending of all of the web elements of each row.

Obviously, the web elements 11 may be bent to positions at right angles to the planes of the rings 10, as shown in Figs. 2 and 5, or their bending may be stopped before they reach positions at right angles to said rings, in which event they will be disposed at inclinations to the planes

of said rings, as shown in Fig. 3, so as to have the air deflecting function heretofore mentioned.

Bending of the web elements 11 along the lines *h* results in corresponding ends of the web elements of each row being connected to the adjacent edge of the ring 10 at one side of the row by the V-shaped elements *f* and in the other ends of said web elements being connected to the adjacent edge of the ring 10 at the other side of the row by the V-shaped elements *g*, which V-shaped elements remain in the planes of the respective rings 10. Thus, sturdy connections are provided between each adjacent two of the rings 10 by the intermediate row of web elements 11 in conjunction with the related V-shaped elements *f* and *g*.

In shifting the rings 10 axially relative to one another the successively larger rings are, of course, displaced successively upwardly to provide for flow of air laterally outward from the device in superimposed layers.

Obviously, the radial spaced apart relationship of the rows of slits *b* and *c* of any given band *a* determines the width of the web elements 11 in that band. Likewise, the length of the slits *b* and *c* in any given band *a* obviously determines the length or height of the web elements 11 in that band. In this connection, while the drawings illustrate all of the web elements 11 as being of equal width and length or height, it is apparent that the web elements of any given row may be of different width, or different length or height, or both different width and different length or height, from the web elements in any other row, to provide openings or passageways 12 of any desired width and length between any two adjacent rings 10 regardless of the width and length of the openings or passageways between any other two adjacent of said rings, and also to space any two adjacent of said rings any desired distance apart axially regardless of the axial spacing of any other adjacent two of said rings. Moreover, it is apparent that the diagonal slits *e* of any given band may be reversed with respect to the diagonal slits *e* in any other band, as this simply will result in a reversal of the V-shaped elements *f* and *g*. Of course, in any given row it is essential that all of the web elements 11 be of equal width and equal length or height.

Obviously, instead of the device comprising more than two rings 10, it may comprise only two rings and a single intervening row of web elements 11 and passageways 12. Moreover, instead of the device being provided with a neck such as the neck 13 for attaching it to an air supply duct, it obviously may be fastened directly to an air supply duct by means of screws, bolts or the like or in any other desired manner. Furthermore, whether the device is fastened to an air supply duct by means of a neck such as the neck 13, or in any other suitable manner, one or more of the rings 10 may be disposed laterally outward with respect to the air outlet opening in the duct and in spaced relationship to the duct, and the neck or other attaching means may be perforate, so that air flowing from the duct through the device will produce a suction effect and an aspirating or inward flow of room or enclosure air into the device through the space, or spaces, above the ring, or rings, 10 which is, or are, disposed laterally outward with respect to the air outlet opening in the duct. For example, if a neck such as the neck 13 is employed for attaching the device to an air supply duct, the neck may be fastened to any one of the rings 10 in-

wardly of the outermost ring and adjacent to its lower end may be provided with openings through which air may flow into the device from the space, or spaces, above the ring, or rings, which are disposed outwardly thereof. In fact, even if the neck is fastened to the outermost ring 10, the latter ring may be spaced from the duct and the neck 13 may have openings 13a therein for flow of air into the device from the space above the said outermost ring 10. Thus, there may be obtained a very desirable mixing within the device and in the immediate vicinity thereof, of the room or enclosure air with the supplied air.

Regarding the neck 13, if same is employed it may be formed in any suitable manner and may be attached to any one of the rings 10 in any suitable manner. For example, said neck may include a bottom horizontal flange 14 which may seat upon one or another of the rings 10 and which may be secured thereto by small bolts 15.

Referring now to the alternative form of the device illustrated in Figs. 8 and 9 of the drawings, the construction is the same as in the first described form of the device, except that the rings, designated as 10a, are of downwardly and outwardly flaring form and are disposed in a common horizontal plane, thereby defining downwardly and outwardly flaring passageways therebetween.

In constructing the Figs. 8 and 9 form of the device in accordance with the method of the invention there first is provided in any suitable manner a basic or pre-formed plate structure A', as shown in Figs. 6 and 7, comprising a series of successively larger frusto-conical ring elements 10a of any suitable sheet material, arranged concentrically and successively downwardly with respect to one another, with the lower and the upper edges of each two adjacent ring elements disposed in approximately a common plane and connected together by a flat ring element 16. Each flat ring element 16 then is provided in any suitable manner with an annular band of slits a' similar to the annular bands of slits a provided in the basic plate structure or disk A of the first described form of the invention to define in each of said ring elements 16 an annular row of web elements 11'. The frusto-conical ring elements 10a then are rotated and shifted axially relative to each other to swing the web elements 11a toward vertical positions to provide an annular series of openings 12a in each of said flat ring elements 16 and also to cause each two adjacent of the frusto-conical ring elements 10a to be connected together at their adjacent edges by the intermediate row of web elements 11a.

The ring elements 10a may be of equal heights and the web elements 11a of each of the bands a' may be of equal lengths or heights and of the same length or height as the ring elements 10a, and in that event rotation and axial shifting of adjacent of the frusto-conical ring elements 10a relative to each other until all of said web elements reach positions at right angles to the planes of said frusto-conical ring elements will result in all of said frusto-conical ring elements being disposed in a common horizontal plane, as shown in Fig. 8. On the other hand, regardless of the length or height of the web elements 11a, of the different rows, the ring elements 10a may be of unequal heights. Likewise, regardless of the length or height of the ring elements 10a the web elements 11a of the different rows may be of unequal lengths or heights. In any such event rotation and axial shifting of adjacent of the frus-

tro-conical ring elements 10a until the web elements 11a are disposed at right angles to the planes of said frusto-conical ring elements 10a will result in the ring elements being disposed either in the same plane or in different planes, depending upon the relative heights of the ring elements and the web elements. In this connection, Fig. 10 of the drawings illustrates by way of example that the web elements 11a of the successively larger rows are successively shorter in length or height and that the successively larger frusto-conical ring elements 10a are of equal heights and are disposed in successively higher planes. Of course, regardless of the length or height of the web elements 11a of the different rows, those in any one or more rows may be bent only to inclined positions relative to the planes of the frusto-conical ring elements 10a so as to act to deflect air in the manner set forth in connection with the inclined web elements 11 illustrated in Fig. 3 of the drawings.

The Figs. 8 to 10 form of the invention preferably includes a suitable neck or its equivalent, designated as 13a, for connecting the device to an air supply duct in air receiving relationship thereto, but as in the case of the Figs. 1 to 5 form of the invention, the device may be secured directly to an air supply duct in any suitable manner. Moreover, the widths of the flat rings 16 may be varied and the slits in said rings may be radially spaced apart any desired distances and may be of any desired lengths to provide web elements 11a of any desired widths and heights and openings 12a of any desired widths and lengths. Furthermore, the Figs. 8 to 10 form of the device may comprise only two rings 10a and a single intervening row of web elements 11a and openings 12a and, as in the case of the Figs. 1 to 5 form of the invention, the device may be mounted with one or more of its ring elements 10a disposed laterally outward of the air outlet opening in the duct for air aspiration purposes as described in connection with the Figs. 1 to 5 form of the invention.

Obviously, according to the Figs. 8 to 10 forms of the invention, air flowing downwardly into the device is divided into separate streams and is deflected laterally outward by the frusto-conical ring elements 10a, whereby it is effectively diffused.

While it may be possible to press or otherwise form from a single sheet of material the basic plate structure shown in Figs. 6 and 7 of the drawings, it is more practical to form the ring elements 10a and 16 separate from each other and to unite them as by soldering, welding or in any other suitable manner.

According to the Figs. 1 to 5 form of the invention the smaller or innermost air intercepting member 10 does not have any opening therein and therefore is in the form of a disk rather than in the form of a ring. Likewise, the smaller or innermost air intercepting members 10a of the Figs. 6 to 9 form of the invention is closed against passage of air therethrough and therefore is not truly a ring. However, for purposes of this specification and the appended claims, said innermost members 10, 10a are to be regarded as rings whether they are completely closed, as shown, against the passage of air therethrough, or whether they are centrally or otherwise open for passage of air therethrough. In other words, when the specification or the claims refers to the rings 10 or 10a, the innermost member 10 or 10a is intended to be in-

cluded whether it is truly a ring or whether it is completely closed against passage of air therethrough, or whether it is provided with an opening or openings other than a central opening for flow of air therethrough.

Without further descripton it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. The method of producing an air outlet device which comprises providing in a plate structure at successively greater distances from the center thereof concentric bands of slits each comprising an inner and an outer row of slits with the slits in each row disposed in end to end spaced apart relationship and the slits of the respective rows of each band disposed in pairs to define web elements therebetween, further providing in said plate structure diagonal slits connecting corresponding adjacent ends of inner and outer slits of adjacent pairs in each band to provide between each two adjacent web elements a pair of substantially V-shaped elements one joined to one end of one of the web elements and to the portion of the plate structure inwardly of the band of slits and the other joined to the adjacent end of the other of the web elements and to the portion of the plate structure outwardly of the band of slits, and rotating and shifting axially relative to each other the portions of the plate structure to each side of each of the bands of slits while controlling bending of said web elements along lines extending between corresponding ends of the pairs of slits to cause said web elements to be swung to positions at angles to the planes of the plate structure between the bands of slits, whereby the adjacent edges of the portions of the plate structure are connected together at their edges by said web elements and said V-shaped elements, and whereby annular rows of air outlet openings are provided in said plate structure.

2. The method of producing an air outlet device from a single piece of flat sheet material which comprises providing in the sheet successively larger concentric bands of slits dividing the sheet into successively larger concentric air intercepting ring-like portions and with each band of slits comprising an inner and an outer row of slits with the slits in each row disposed in end to end spaced apart relationship and the slits of the respective rows of each band disposed in pairs to define web elements therebetween, further providing in the sheet diagonal slits connecting corresponding adjacent ends of inner and outer slits of adjacent pairs in each band to provide between each two adjacent web elements a pair of substantially V-shaped elements one joined to one end of one of the web elements and to the ring-like portion of the sheet inwardly of the band of slits and the other joined to the adjacent end of the other of the web elements and to the ring-like portion of the sheet outwardly of the band of slits, and rotating and shifting axially relative to each other the ring-like portions of the sheet to each side of each band of said slits while controlling bending of said web elements along lines extending between corresponding ends of the pairs of slits to cause the web elements to be swung to posi-

tions at angles to the planes of the ring-like portions of the sheet, whereby the ring-like portions are caused to be connected together at their adjacent edges by said web elements and said V-shaped elements, and whereby annular rows of air outlet openings are provided in the sheet between the air intercepting ring-like portions thereof.

3. An air outlet device comprising a first horizontally disposed air intercepting and deflecting element, a second horizontally disposed air intercepting and deflecting element disposed outwardly with respect to said first air intercepting and deflecting element and having its inner edge spaced outwardly from and above the outer edge of said first air intercepting and deflecting element, substantially straight substantially vertically disposed web elements between the said edges of said air intercepting and deflecting elements, flat substantially horizontally disposed web elements at the lower ends of said substantially vertically disposed web elements connecting the lower ends of said substantially vertically disposed web elements to the outer edge of said first air intercepting and deflecting element, and other flat substantially horizontally disposed web elements at the upper ends of said substantially vertically disposed web elements connecting the upper ends of said substantially vertically disposed web elements to the inner edge of said second air intercepting and deflecting element.

4. An air outlet device as set forth in claim 3 in which the web element at one end of each substantially vertically disposed web element extends from the latter web element in a direction opposite to the web element at the other end thereof.

5. An air outlet device as set forth in claim 3 in which the air intercepting and deflecting elements are of flat plate form.

6. An air outlet device as set forth in claim 3 in which the air intercepting and deflecting elements are inclined downwardly and outwardly.

7. An air outlet device as set forth in claim 3 in which the air intercepting and deflecting elements are inclined downwardly and outwardly and are disposed in a common horizontal plane.

8. An air outlet device comprising a first horizontally disposed annular air intercepting and deflecting element, a second horizontally disposed air intercepting and deflecting element of ring-like form disposed outwardly with respect to said first air intercepting and deflecting element and having its inner edge spaced outwardly from and above the outer edge of said first air intercepting and deflecting element, an annular row of annularly spaced apart straight substantially vertically and substantially radially disposed web elements between said edges of said air intercepting and deflecting elements, flat substantially horizontally disposed web elements at the lower ends of said substantially vertically disposed web elements in the plane of the outer edge of said first air intercepting and deflecting element connecting the lower ends of said substantially vertically disposed web elements to the said outer edge of said first air intercepting and deflecting element, and other flat substantially horizontally disposed web elements at the upper ends of said substantially vertically disposed web elements in the plane of the inner edge of said second air intercepting and deflecting element connecting the upper ends of said substantially vertically disposed web elements to the said inner edge of said second air intercepting and deflecting element.

9. An air outlet device as set forth in claim 8

in which the web element at one end of each substantially vertically disposed web element extends from the latter web element in a direction opposite to the web element at the other end thereof and in which adjacent edges of adjacent upper and lower web elements are spaced apart annularly of the device.

10. An air outlet device as set forth in claim 8 in which the air intercepting and deflecting elements are of flat plate form.

11. An air outlet device as set forth in claim 8 in which the air intercepting and deflecting elements are of frustro-conical form.

12. An air outlet device as set forth in claim 8 in which the air intercepting and deflecting elements are of frustro-conical form and disposed in a common horizontal plane.

13. The method of producing an air outlet device which comprises providing a plate structure including a first frustro-conical portion, a second larger frustro-conical portion and a flat ring-like portion connecting the larger end of the first frustro-conical portion with the smaller end of the second frustro-conical portion, providing in said flat ring-like portion an annular band of slits comprising an inner and an outer row of slits with the slits in each row disposed in end to end spaced apart relationship and the slits of the respective rows disposed in pairs to define web elements therebetween, further providing in said ring-like portion diagonal slits connecting adjacent ends of inner and outer slits of adjacent pairs to provide between each two adjacent web elements V-shaped elements one joined to one end of one of the web elements and to the portion of the plate structure inwardly of the band of slits and the other joined to the adjacent end of the other web element and to the portion of the plate structure outwardly of the band of slits, and rotating said frustro-conical portions with respect to one another and shifting them toward one another while limiting bending of said web elements to a pair of straight parallel lines extending between the ends of the pairs of slits to cause said web elements to be swung toward positions at right angles to the planes of said frustro-conical portions and by their swinging to provide an annular row of air outlet openings between said frustro-conical portions.

14. An air outlet device comprising a horizontally disposed air intercepting and deflecting element, a second element disposed horizontally and outwardly with respect to said air intercepting and deflecting element and having its inner edge spaced outwardly from and above the outer edge of said air intercepting and deflecting element, substantially straight substantially vertically disposed web elements between the said edges of said elements, flat substantially horizontally disposed web elements at the lower ends of said substantially vertically disposed web elements connecting the lower ends of said substantially vertically disposed web elements to the outer edge of said air intercepting and deflecting element, and other flat substantially horizontally disposed web elements at the upper ends of said substantially vertically disposed web elements connecting the upper ends of said substantially vertically disposed web elements to the inner edge of said second element.

15. An air outlet device comprising a horizontally disposed annular air intercepting and deflecting element, a second element of ring-like form disposed horizontally and outwardly with respect to said air intercepting and deflecting element and having its inner edge spaced outwardly from and above the outer edge of said air intercepting and deflecting element, an annular row of annularly spaced apart straight substantially vertically and substantially radially disposed web elements between said edges of said elements, flat substantially horizontally disposed web elements at the lower ends of said substantially vertically disposed web elements in the plane of the outer edge of said air intercepting and deflecting element connecting the lower ends of said substantially vertically disposed web elements to the said outer edge of said air intercepting and deflecting element, and other flat substantially horizontally disposed web elements at the upper ends of said substantially vertically disposed web elements in the plane of the inner edge of said second element connecting the upper ends of said substantially vertically disposed web elements to the said inner edge of said second element.

FRIEDRICH HONERKAMP.
